UNITED STATES PATENT OFFICE.

WILLIAM C. JOHNSTON, JR., OF LYNN, MASSACHUSETTS.

ELECTRIC COUPLING FOR RAILWAY-TRAIN SIGNALING.

SPECIFICATION forming part of Letters Patent No. 397,553, dated February 12, 1889.

Application filed March 5, 1888. Serial No. 266,116. (No model.)

To all whom it may concern:

Be it known that I, WILLIAM C. JOHNSTON, Jr., of Lynn, county of Essex, and Commonwealth of Massachusetts, have invented Improvements in Electric Signaling Apparatus for Railway-Trains, of which the following, taken in connection with the accompanying drawings, is a specification.

This invention relates to improvements in electric signal apparatus for use on railway-trains, and the nature thereof is hereinafter fully described and specifically claimed.

Referring to the drawings, Figure 1 is a perspective view representing a coupling embodying this invention. Fig. 2 is a side elevation representing the two parts of the coupling locked together and the outer shell being broken away to represent the mechanism inclosed thereby. Fig. 3 is the same as Fig. 2, except that it represents the two parts of the coupling detached.

The shell or casing A is composed of wood or other non-conducting material. It is desirable to have it composed of material light as possible, and I prefer to make it of wood and cover it with a coating of enamel, which is baked thereon in the usual manner of enameling wooden articles. It is provided with longitudinal chambers or channels *h*, in which are pivoted the levers *a* *b*, as represented in Figs. 2 and 3. The case B is also provided in a similar manner with pivoted levers *4* *4*. In other respects the case B is a duplicate of the case A. Said cases A and B are provided on one end with sectional flanges *6*, that dovetail with each other when the coupling is closed together and form a shield or covering to prevent the dust and cinders from passing in between the contiguous ends of the coupling to disturb the action of the mechanical parts or levers. The cases are provided each with a metallic ring, 7, which ring is attached to the rear end of the case and is provided with an extension, 8, and connected with the levers *a* *b* *4* *4* are springs 9, which operate to hold the ends of the levers, respectively, against the ring 7 when the coupling is drawn apart, as shown in Fig. 3. Said levers are provided on their front ends, respectively, 50 with a double inclined boss, 10.

The electric conducting-wires are attached, one, which may be the direct, to one of the

levers, and the other, which may be the return, to the other of said levers. In each case the conducting-wires traverse the entire car, 55 and a case is secured to the wires at each end of the car in the usual manner. At the rear end of each case is a tube, 12, composed of rubber or similar flexible material, which surrounds the conducting-wire, and is provided 60 with a flange on its inner end, that is impinged between the end of the case and a screw-cap, 15. The other end of said tube is extended outward from the case through said cap and is wound tightly to the conducting- 65 wires. In this manner dust and dampness are prevented from entering the case or interfering with the action of the conducting-wires at this point.

The normal position of the levers *a* *b* *4* *4* 70 when the cases are drawn apart is represented in Fig. 3, and their normal position when the cases are coupled together is represented in Fig. 2. The cases are coupled together by bringing them to each other with the 75 inclined faces of the levers lined with each other and pushing the cases together, allowing the levers to pass each other and interlock, as shown in Fig. 2, in which position the respective levers operate to hold each other out of contact with the metallic ring 7, and thus establish 80 direct communication from the respective conductors in one car or section and those of the other car or section through the intermediate levers. The conductors are thus made complete and continuous and also independent of 85 each other from one end of the line to the other. When the cases are drawn apart, which may be effected by pulling the cases in opposite directions, the springs 9 operate 90 to automatically force the levers into contact with the ring 7, and thus establish a connection between the conducting-wires through the intermediate ring.

The cases are held together by the levers *a* *b* *4* *4* interlocking each other, as shown in Fig. 2. The inclined bosses 10 on the levers operate to hold each other, and this effect is increased by action of the springs 9, against the tension of which the levers are held when 100 interlocked.

I claim—

1. The combination of the two-part separable conductor A B, having the conducting-

rings 7 7, the pivoted levers *a b* 4 4, pivotally supported in the parts of the coupling, an electric conductor attached to each pivoted lever, the levers *a b* being adapted to engage with levers 4 4 when the coupling is closed, thus establishing electric connection between the conductors attached to one part of the coupling and those attached to the other part, and means for automatically establishing connection between the conductors and metallic rings 7 when the parts of the coupling are separated, substantially as described.

2. In a coupling for uniting the detached sections of a direct and return conductor con-

stituting a railway-train signaling-circuit, the 15 combination of a shell or case, as A, and with the conducting-wires, a flanged tubular section of flexible material, as 12, for inclosing the wires, and a screw-cap, as 15, for securing said tubular section to the casing, substantially as described.

Signed at Boston, Massachusetts, this 29th day of February, A. D. 1888.

WM. C. JOHNSTON, JR.
